UNITED STATES PATENT OFFICE.

WILLIAM STUEBING, JR., OF CINCINNATI, OHIO, ASSIGNOR TO THE STUEBING TRUCK COMPANY, OF CINCINNATI, OHIO, A CORPORATION OF OHIO.

LIFTING TRUCK.

Application filed October 8, 1917. Serial No. 195,326.

To all whom it may concern:

Be it known that I, WILLIAM STUEBING, Jr., a citizen of the United States, residing at Cincinnati, in the county of Hamilton and 5 State of Ohio, have invented certain new and useful Improvements in Lifting Trucks, of which the following is a specification.

My invention belongs to that class of "trucks" known as "lifting trucks", having a 10 base frame and an elevating platform movable up and down with respect thereto.

Trucks of this class are usually used in connection with raised platforms upon which the goods, articles or merchandise to be 15 moved or trucked is placed; the truck when lowered being capable of being moved in under the raised platform and by movement of the handle, the elevating platform is elevated lifting the raised platform with the 20 goods, up off of the floor; the truck can then be moved to any point carrying the raised platform and goods, and when this point is reached the elevated platform can be lowered depositing the raised platform and its 25 load; the truck can then be pulled out from under the raised platform. Many of these raised platforms can be used and with the goods upon them, may be trucked at will to any place desired. These lifting trucks can 30 also be run in under machinery or other articles admitting of such entry and trucked to any point desired without the use of such raised platforms, or can be used in connection 35 with platforms of peculiar construction, or temporarily made for special use and conveyance.

While the truck which I have now evolved may be used satisfactorily for transporting light or ordinary loads of a minimum or 40 heavier weight, it is especially designed and constructed for lifting and transporting loads of a very heavy or maximum weight.

The mechanism employed between the lifting truck platform and the handle for raising 45 the load, is of a simple, unique and highly efficient construction and nature, enabling me to elevate the lifting platform both by the downward and upward movement of the handle.

50 This truck is not only very powerful but strong and yet very simple in outline and construction.

One of the salient features of the invention consists in the use or employment of a pivoted U shaped link having two hooks or 55 catches on each of its arms, and further in the employment of two single independently mounted hook arms operating automatically in connection therewith so that the handle lever which carries two sets of engagement pins can be used in connection 60 with both the U shaped link and the separate arms, so that the movement of the handle lever downward and upward enables the pins on said handle lever to alternately engage 65 said mechanism to force an elevating of the elevating platform on both the downward and upward movement of said handle.

These links and hook arms readily and automatically pass back into normal position 70 when released from engagement with the handle lever.

In the following description I explain and 75 illustrate one specific means for carrying my invention into effect.

In the accompanying drawings, forming part of this specification:

Fig. 1, is a plan view of the machine,

Fig. 2, is a side elevation of Fig. 1,

Fig. 3, is a side view of Fig. 2 with part of 80 the frame broken away to show the lifting mechanism of the truck,

Fig. 4, is the same view as Fig. 3, showing the lifting mechanism in a different position.

Fig. 5, is the same view as shown in Fig. 85 4, with the lifting mechanism in another position,

Fig. 6, is a side elevation partly broken away showing the check mechanism and the platform in a raised position with the lifting 90 mechanism disconnected from the handle,

Fig. 7, is a reverse view of Fig. 2 with the elevating platform in a raised locked position showing the mechanism disconnected from the handle.

Fig. 8, is a side elevation of the truck with the lifting mechanism partly broken away and the elevating platform partly elevated,

Fig. 9, is the same view as Fig. 7, showing the lifting mechanism connected to the 100 handle,

Fig. 10, is the same as Figure 3, with the lifting mechanism and handle in a different position,

Fig. 11, is a plan view of the lifting mechanism and treadle with the frame of the truck broken away,

Fig. 12, is a side elevation of the lifting hooks and partly broken away to show the spring connection between the hooks.

Fig. 13, is same view as shown in Fig. 7, with the platform in its lowered position, the lifting mechanism disconnected from 10 the handle, being free for steering, and

Fig. 14, is a front elevation of the truck.

The base is composed of four bars 14. These bars extend from the head 13 to the shaft 8 and they are fastened together at the rear 15 by bolts 16 and at the front by bolts 17 and 18. The base frame carries four wheels 76 at the rear on the axle 8 and at the front one wheel 21 is provided.

The elevating platform or upper frame 20 is composed of four bars 1 connected at the rear by the tie bar 2 and at the front by the saddle 3.

The elevating platform is suitably mounted on the base frame by the links 4, rod 5 and the links 6 and 7 on the rear on shaft 8 and at the front is mounted by the links 9, upper studs 10 and lower studs 12 to the head 13. By means of this construction the upper frame is pivotally mounted on the base frame and can thus swing up and down and horizontally. The upper frame or lifting platform as well as the base frame may be made of any other approved form.

The head 13, at its center, has the bearing 19, in which I swivel the fork 20. At the lower end of this fork 20, I mount the wheel 21 by means of the shaft 22. The upper end of the swivel 20 carries the bearing 23, which supports the shaft 24; on the shaft 24 I 40 mount the handle 25. The handle 25 carries the pins 26 placed above the shaft 24. Handle 25 also has pins 27 placed opposite to pins 26 and below them, as shown in Fig. 3.

On the saddle 3, I place the bearings 32, 45 as shown in Fig. 1, and these bearings carry the shaft 28 upon which I pivotally mount the link or double hook 29. This link carries the shaft 30 upon which I mount two hook arms 31 which are similar in design, as 50 shown in Fig. 1. The link 29 at the points 55 50 and 51 and the hooks 31 at the points 60 are so mounted and arranged as to connect with the pins 26 and 27 of the handle 25 when said handle is moved down and up. 55 On said shaft 28, I also mount the locking hook 33, which has a lug 34 at one of its sides, which lug extends out laterally under the double hook or link 29, as shown in Figs. 7 and 11. On the head 13 I fasten the holding hook 36, which has an engaging portion 37 which meshes with hook 33 when the lifting platform is in a raised position, to maintain the lifting platform in said position, (see Fig. 7.)

65 On the head 13, I place the bearing 38 to

which I pivotally connect the treadle 39, which has a rearwardly extending portion 40 and a forwardly extending portion 41; the rearwardly extending portion 40 of the treadle 39 being placed under the pin 35 of 70 the locking hook 33 and said pin 35 riding upon the portion 40 as a track when the elevating platform is being raised.

The double link or lifting hook 29 on shaft 28 and the lifting hook arms 31 on shaft 30 75 are connected together by means of the springs 42 and the action between the link 29 and the hook arms 31 is limited by means of the stops 43 on the hooks 31, as shown in Fig. 12. The initial strain in lifting the 80 elevating platform when the handle is lowered comes first on shaft 28 which carries link 29, designated by line X—X, Fig. 3, and the shaft 30 is in such a position and so mounted that it will receive this line of strain 85 when the handle is elevated. This will be more fully described hereinafter.

Between the bars 14 near the middle of the truck, I fasten the beam 44 and between this beam and the saddle 3, I suitably mount 90 and fasten the fluid check device 45 which carries a spring 46 inside of the cylinder as shown in Fig. 6, to release the elevating platform, when the locking hook 33 is disconnected, this spring having been placed 95 under stress when the elevating platform was lifted.

The link 29 is U shaped having two side arms united at their rear to form an integral member. The two hooks 50 and 51 are present at the forward part of each arm. The hook arms 31 are each independently mounted and each carry the hook 60.

This link and the hook arms may be made of any desired contour and constructed in 100 any suitable way to best carry out their functions.

The truck operates as follows, to wit: The operator steps on the treadle 39; this raises the rearward extension 40 of said treadle 110 and in this raising movement the pin 35 is forced upwardly, consequently the hook 33 is lifted and its lug extending in under the link 29, raises the said link into connection with the pins 26 on the handle 25, they entering the hooks 50 of said link. The handle, in order to accomplish this engagement must be held in a proper upright position to meet the hooks 50 as they come up when the link 29 lifts, see for example Figs. 3 120 and 9.

In Fig. 13, the elevating platform is in its lowest position and the means for connecting to the handle disconnected from the handle. This is the position of the parts 125 when the operator is ready to connect the handle and link 29, except that the handle must be raised to a vertical position.

Fig. 7 is a somewhat similar view but showing the elevating platform in elevated 130

position, the hooks 29 and 31 having dropped down, the handle being shown elevated to better show how the parts are positioned to clear the handle for steering.

5 In Fig. 3, the link 29 is connected to pins 26 on the handle, showing said pins in the hooks 50 of the link and the hook 60 of the hook arms 51 in position to meet with pins 27 on the handle 25 through agency of 10 springs 42, said springs 42 holding the hook arms 31 against the pins 27 on the handle 25 in which position the pins 27 will connect into hooks 60 of said hook arms 31, when said handle 25 is lowered. In this position 15 the operator pulls down the handle, and through the agency of the link 29 and pins 26, raises the elevating platform 1 to a height shown in Fig. 4. It may be here remarked that when the lifting mechanism is connected 20 as described and shown in Fig. 3, the line of elevating force between the elevating platform and the handle is on line X—X. In Fig. 4, the line X—X is shown with the elevating platform and handle in another position. The lifting force in Figs. 3 and 4 is 25 shown through the center of the lifting link 29 and pins 26 of the handle. In Fig. 4 it will be noted the handle is in its lowest position with the link 29 through the agency of 30 hooks 50 in connection with pins 26 of the handle, and the arms 31 through agency of hooks 60 connected to pins 27 of the handle. The operator now lifts the handle upwardly, 35 as shown in Fig. 10, the hook arms 31 through agency of hooks 60 being connected to pins 27 the upward movement will further raise the elevating platform 1, thus changing the position of line X, X, through the center of shaft 28, shaft 30 and pins 27, thus 40 causing link 29 to raise, (see Fig. 10).

In Fig. 10 the handle is partly raised to start on the above described operation. It will be noted that pins 26 are riding into a position to connect automatically in hooks 45 51. The link 29 is held in automatic connecting relation with the pins 26 through agency of the elevating force, on line X—X. When the handle 25 is now moved upward the pins 26 are moved forward with the handle 50 and as soon as they reach the hook 51, the hook parts 51 will receive the said pins 26 as the link 29 moves upward when this point is reached and assumes the position shown in Fig. 5. This movement elevates the lifting 55 platform 1 to a still higher degree as shown in said figure, the handle being again in a vertical position and the hooks 60 of hook arms 31 being still in connection with the pins 27 on handle 25, and the line of elevating force 60 is on line X—X and this force changes its position only when the handle is again brought down as shown in Fig. 8. The next step in the elevating compels the operator to again lower the handle from the position

shown in said Fig. 5, and Fig. 8 shows the 65 handle 25 partly lowered, the hooks 51 of link 29 engaging pins 26 on the handle and the pins 27 having the position in hook 60 of hook arms 31, the arms 31 having ridden under the said pins 27 through agency of 70 springs 42, and the line of elevating force X—X has taken its original position as seen in Fig. 3.

As the operator now pulls down the handle with its pins 26 connected in hooks 51, 75 as shown in Fig. 8, the platform 1 will be elevated to its highest point and will be maintained in that position by the holding and locking means.

Figure 6 shows the pedal in position 80 whereby hook 33 is disconnected from hook 37 on head 13, this relieves the stress on spring 46 of the fluid check device and the spring pulls down the platform or gives it an initial impetus as the case may be and 85 consequently the elevating platform 1 lowers automatically to lowest (normal) position; Fig. 7 is a similar view to that shown in Fig. 6, but the holding hook which holds up the elevating platform in raised position is not 90 disconnected. The elevating platform is here shown at its highest limit.

Fig. 9 is a view similar to that shown in Fig. 3, however, showing an opposite side of the truck, with the mechanism for lifting 95 the link 29 and hook arms 31 in operative position with handle 25. During this last operation when the handle is pulled down, the elevating platform is locked in its raised, elevated position by means of the locking 100 hook 33 meshing with the holding hook 36 on the head 13. When the elevating platform has reached the extent of its upward movement and is held locked in position as above described, as soon as the handle is 105 raised the link and arms fall out of connected position with the handle, so that the handle can freely be used for steering purposes. To release the elevating platform from its raised locked position the operator 110 steps on the pedal 39; this raises the extension 40 of said treadle which pressing upward on the pin 35 of the hook 33 disconnects the hook 33 from the surface 37 of the hook 36 and the elevating platform is brought 115 to its normal position again by reason of the stress being relieved on spring 46 in the check 45, see Fig. 6.

While I have described one means for carrying my invention into effect, I wish to 120 be understood as not limiting myself to the construction herein shown and described, as the same is capable of considerable change and modification without departure from the principle and spirit of the invention, and I 125 wish to be understood as claiming that such modifications will still fall within the scope of my invention.

- What I claim as new and my invention and desire to secure by Letters Patent is:
1. In a lifting truck, the combination with a wheeled base, an elevating platform and pivoted steering handle, of means for connecting said platform to said handle to elevate said platform, comprising a hinged coupling member having double hooked arms and carrying two independently hinged hook arms, and means for raising said coupling member into engagement with the handle.
  2. In a lifting truck, the combination with a wheeled base, an elevating platform mounted on said base, a pivoted handle at one end of said base for wheeling and steering the load and elevating said platform, means for connecting said handle and platform for elevating the latter, comprising rigid coupling members on one of said parts, and a hinged coupling member connected to the other of said parts normally out of connecting range with said rigid coupling members and adapted to be moved into connection therewith for elevating said platform, said hinged coupling member carrying two separate sets of hook arms, said hook arms adapted to engage certain of the rigid members at predetermined times during the raising of the elevating platform.
  3. In a lifting truck, the combination with a wheeled base, an elevating platform mounted on said base, a pivoted handle at one end of said base for wheeling and steering the load and elevating said platform, means for connecting said handle and platform for elevating the latter, consisting of rigid means on the handle and a hinged member on the platform carrying hook arms, said hinged member and said hook arms adapted to engage the rigid means on the handle at predetermined times as the handle is lowered and raised to elevate the lifting platform.
  4. In a lifting truck, the combination with a wheeled base, an elevating platform mounted on said base, a pivoted handle at one end of said base for wheeling and steering the load and elevating said platform, means for connecting said handle and platform for elevating the latter comprising two sets of pins on said handle and a pivoted link on the platform provided with hooks, said link carrying two independently mounted hook arms, said link and hook arms engaging and disengaging the said pins during the downward and upward stroke of the handle, as the lifting platform is being elevated.
  5. In a lifting truck, the combination with a wheeled base, an elevating platform mounted on said base, a pivoted handle at one end of said base for wheeling and steering the load and elevating said platform, means for holding the platform against retrograde movement between said steps, and means separate from the last-named means for holding the platform in its completely elevated position.
  6. In a lifting truck, the combination with a wheeled base, an elevating platform mounted on said base, a pivoted handle at one end of said base for wheeling and steering the load and elevating said platform, means on the handle for engaging therewith to form a platform elevating means, operable to raise the platform during both the downward and upward movement of the handle,
  7. In a lifting truck, the combination with a wheeled base of an elevating platform mounted thereon, a pivoted handle at one end of said base for elevating said platform and for wheeling and steering the load, pivoted means between the elevating platform and said handle operable to raise the platform during both the downward and upward movement of the handle, said means capable of being connected and disconnected.
  8. In a lifting truck, the combination with a base, an elevating platform and a pivoted steering handle, of means for connecting said platform to said handle to elevate said platform, comprising a member normally out of connecting position when the handle is used for steering, the means for connecting said platform to said handle to elevate said platform capable of elevating said platform on both the downward and upward stroke of said handle.
  9. In a lifting truck, the combination with a wheeled base, an elevating platform mounted on said base, a pivoted handle at one end of said base for wheeling and steering the load and elevating said platform, means on the elevating platform, means on the handle for engaging therewith to form a platform elevating means, operable to raise the platform during both the downward and upward movement of the handle.
  10. In an elevating truck, running wheels, a platform mounted for elevating movement thereon, means for elevating the platform in successive steps, means for holding the platform against retrograde movement between said steps, and means separate from the last-named means for holding the platform in its completely elevated position.
  11. In an elevating truck, running wheels, a platform mounted for elevating movement

thereon, means for elevating the platform in successive steps, means for holding the platform against retrograde movement between said steps, means separated from the last 5 named means for holding the platform in its completely elevated position, said first named holding means being constructed and arranged to remain inoperative during the lowering of the platform from its maximum elevation.

12. In an elevating truck in combination, running wheels, a platform mounted for elevating movement thereon, a pivoted steering handle for said truck, means for elevating 15 said platform in a step by step manner by the successive swinging of said handle, comprising a link for effecting a direct connection between said handle and said platform.

13. In an elevating truck in combination, running wheels, a platform mounted for elevating movement thereon, a pivoted steering handle for said truck, means for elevating 20 said platform in a step by step manner by the successive swinging of said handle com-

prising a link for effecting a direct connection between said handle and said platform during the swinging movements of said handle in one direction, said connection being interrupted during the swinging movements of the handle in the other direction and means for holding the platform in its partially elevated position during the interruption of said connection.

14. In an elevating truck in combination, 30 running wheels, a swivelled steering head, a platform mounted for elevating movement, an operating lever pivoted on said steering head, means for elevating said platform by swinging said lever, comprising a link pivotally connected to one of said parts and having a plurality of hooked portions for successive engagement with the other part.

In testimony whereof I affix my signature in the presence of two witnesses.
